US00D980920S

(12) **United States Design Patent** (10) **Patent No.:** **US D980,920 S**
Ma (45) **Date of Patent:** **** Mar. 14, 2023**

(54) **TOY VEHICLE**

(71) Applicant: **SLIS, Inc.**, Darien, IL (US)

(72) Inventor: **Jiadong Ma**, Darien, IL (US)

(73) Assignee: **SLIS, Inc.**, Darien, IL (US)

(**) Term: **15 Years**

(21) Appl. No.: **29/732,594**

(22) Filed: **Apr. 26, 2020**

(30) **Foreign Application Priority Data**

(57) **CLAIM**

The ornamental design for a toy vehicle, as shown and described.

DESCRIPTION

FIG. 1 is a perspective view of a toy vehicle having my design;

FIG. 2 is a front view of the toy vehicle of FIG. 1;

FIG. 3 is a rearview of the toy vehicle of FIG. 1;

FIG. 4 is a left side view of the toy vehicle of FIG. 1;

FIG. 5 is a right side view of the toy vehicle of FIG. 1;

FIG. 6 is a top view of the toy vehicle of FIG. 1; and,

FIG. 7 is a bottom view of the toy vehicle of FIG. 1.

Features shown in dashed lines are features of the toy vehicle that form no part of the design claimed.

1 Claim, 7 Drawing Sheets
